UNITED STATES PATENT OFFICE.

JOSEPH A. SIMMS, OF DETROIT, MICHIGAN, ASSIGNOR OF ONE-HALF TO JAMES H. GREGG AND GEORGE A. GREGG AND ONE-FOURTH TO ANTHONY LASZLO, ALL OF DETROIT, MICHIGAN.

MOTOR.

1,297,263.

Specification of Letters Patent. Patented Mar. 11, 1919.

Application filed November 22, 1917. Serial No. 203,337.

To all whom it may concern:

Be it known that I, JOSEPH A. SIMMS, citizen of the United States, residing at Detroit, county of Wayne, State of Michigan, have invented a certain new and useful Improvement in Motors, and declare the following to be a full, clear, and exact description of the same, such as will enable others skilled in the art to which it pertains to make and use the same, reference being had to the accompanying drawings, which form a part of this specification.

My invention relates to a combined internal combustion engine and steam engine; the construction being such that the heat from the exhaust gases and also the radiation resulting from the operation of the internal combustion cylinder, or cylinders, is utilized to generate steam for delivery to the cylinder of the steam engine,—the pistons of the respective cylinders being adapted to act upon the same crank-shaft.

It is well known in this art that the thermal efficiency of the average gasoline or kerosene engine is only about 27% and that the other 73% is lost. The most efficient engine known at present shows a thermal efficiency of 38%, but owing to high compression,—approximately 500 pounds per square inch,—this type of engine is necessarily of very heavy construction and therefore impracticable for aeronautic purposes.

It is therefore one of the objects of this invention to provide an economical motive power especially applicable to air vehicles.

A further object of this invention is the elimination of the usual starting devices, the reversing gear with its resulting weight, by the employment of a steam engine forming part of the power unit and whereby the motor may be started and its operation reversed.

A further object is to provide for the operation of this device independent of the operation of the internal combustion engine, whereby in an emergency the steam side of the motor may continue the services of the whole motor after the additional or emergency heater is brought into action.

With the foregoing and other objects in view, which will appear as the description proceeds, the invention further resides in the combination and arrangement of parts and in the details of construction hereinafter described and claimed, it being understood that changes may be made in the embodied

ment of the invention herein described without departing from the spirit of the same.

The accompanying drawing is a diagrammatic, vertical, cross-sectional view of a motor embodying my invention,—with parts in elevation.

Referring to the letters of reference spread upon the drawing: A denotes a four cycle internal combustion engine, and B, a separate double acting steam cylinder operating upon a crank-shaft C. A^a, indicates a water jacket surrounding the cylinder of the internal combustion engine, serving as a steam boiler for the steam cylinder B. D, 60 denotes a coil in the water jacket through which passes the exhaust gases from the internal combustion engine for heating the surrounding body of water. The coil D, is also connected with the jacket B^b, of the steam cylinder to warm the latter. D', is a pipe leading from the jacket B^b, for the discharge of the exhaust gases.

A', indicates the piston of the combustion engine and A², its pitman connected with 80 the crank shaft C. B', denotes the piston of the steam cylinder, and B², the pitman of the latter—also connected with the crank shaft C:—the present embodiment showing both pitmen connected with the same “throw” of 85 the crank shaft,—this however is not essential.

a, indicates a steam dome with which the jacket A^a, of the combustion cylinder is connected. E, is a steam pipe connecting the 90 steam dome with the steam chest of the cylinder B. F, indicates a slide valve for controlling the admission of steam to the cylinder, and F', is a rod for operating the valve, actuated in the usual manner from the crank 95 shaft C. G, G are the steam inlet ports of the cylinder, controlled by the slide valve F. G', is the exhaust port of the cylinder.

H, designates a fuel supply pipe connected with a carburetor I,—preferably of the kerosene-gasoline type, in turn connected by a fuel pipe with the chamber of the inlet valve J, controlling the admission of fuel to the combustion chamber of the engine.

K, designates a valve controlling the 105 delivery of the exhaust gases from the cylinder into the coil D. The operation of the valves J, and K, are controlled through levers actuated by a suitable cam shaft L, in the usual manner. M, indicates diagrammatically a blow-burner connected with the coil D, to start the generation of steam, it 110

may also be used for steam forcing, or for emergency purposes if required.

Having indicated the several parts by reference letters the construction and operation of the motor will be readily understood.

Steam having been generated by means of the blow-burner to actuate the steam engine, the motor is "turned over," causing the combustion engine to operate under its own power, the fuel charge delivered thereto being fired in the usual manner. The exhaust gases from the combustion engine passing out through the coil in the water jacket, generating steam which is delivered to the steam cylinder to actuate the piston of the latter as previously indicated and in a manner readily understood. It will be apparent that this type of motor in an emergency is not dependent upon the operation of its combustion engine and the electrical and mechanical equipment of the latter,—but may be operated by the steam engine, thereby continuing its services as a motor by means of the blow-burner or auxiliary heater.

Having thus described my invention what I claim is:—

1. A prime mover unit including an internal combustion engine, a steam engine having a cylinder arranged at an acute angle to the cylinder of the combustion engine with its inner end contiguous to the inner end of the same, a water jacket adjacent to the cylinder of the internal combustion engine, a steam chamber communicating with the water jacket, a coil housed in said jacket and surrounding the cylinder of the combustion engine and adapted to receive the exhaust gases from the combustion chamber, a jacket arranged adjacent the cylinder of the steam engine and connected with the said coil, and means for delivering steam from the steam chamber to the steam engine to operate the latter.

2. A prime mover unit, including an internal combustion engine, a steam engine having a cylinder secured at its inner end to the inner end of the cylinder of the combustion engine and arranged at an acute angle thereto, a crank-shaft adapted to be actuated by either engine or through the simultaneous operation of both engines, a water jacket surrounding the cylinder of the internal combustion engine, a coil housed in said jacket adapted to receive the exhaust gases of the combustion engine, a steam chamber communicating with the water jacket, a jacket arranged adjacent the cylinder of the steam engine and connected with the said coil, and means for delivering the steam therefrom to the cylinder of the steam engine.

3. A prime mover unit, including an internal combustion engine, a steam engine having a cylinder secured at its inner end to the inner end of the cylinder of the combustion engine and arranged at an acute angle thereto, a water jacket adjacent to the cylinder of the internal combustion engine, a steam chamber in communication with the water jacket, a coil housed in the water jacket adapted to receive the exhaust gases from the combustion cylinder, a jacket adjacent to the steam cylinder in communication with said coil, whereby the exhaust gases may be further utilized to heat the steam cylinder, means for exhausting the gases from said jacket, and means for delivering steam from the steam chamber to the steam engine to operate the latter.

4. A prime mover, including an internal combustion engine, a steam engine, a water jacket adjacent to the cylinder of the internal combustion engine, a steam chamber communicating with the water jacket, a coil housed in said jacket adapted to receive the exhaust gases of the combustion chamber to heat the water in said jacket, an auxiliary heater communicating with said coil, and means for delivering steam from the steam chamber to the steam engine to operate the latter.

5. A prime mover unit including an internal combustion engine provided with a crank case, a steam engine having a cylinder mounted on the crank case with its inner end contiguous to the inner end of the cylinder of the combustion engine, said cylinders being arranged at an acute angle to each other, a crank shaft operating in the crank case, pitmen arranged at an acute angle to each other and connected with the crank and the pistons of the cylinders of the internal combustion engine and the steam engine, a water jacket adjacent the cylinder of the internal combustion engine, a steam chamber communicating with the water jacket, valve mechanism located between the cylinders and also connected with the said crank shaft for controlling the delivery of steam from the steam chamber to the cylinder of the steam engine, a jacket arranged adjacent to the sides and ends of the cylinder of the steam engine and a coil surrounding the cylinder of the combustion engine and arranged in the jacket thereof and connected with the inner end of the jacket of the cylinder of the steam engine.

In testimony whereof, I sign this specification in the presence of two witnesses.

JOSEPH A. SIMMS.
